UNITED STATES PATENT OFFICE.

HOWARD R. HUGHES, OF NEW YORK, N. Y.

METHOD OF AND APPARATUS FOR FORMING AND ENLARGING OR CAVATING BORES.

1,269,449.

Specification of Letters Patent. Patented June 11, 1918.

Application filed May 11, 1916. Serial No. 96,764.

To all whom it may concern:

Be it known that I, HOWARD R. HUGHES, a citizen of the United States, residing in New York, in the county of New York and 5 State of New York, have invented certain new and useful Improvements in Methods of and Apparatus for Forming and Enlarging or Cavating Bores, of which the following is a specification.

10 The present invention relates to a method of and an apparatus for digging or drilling a bore or tunnel in the ground through earth, rock or other material in either a vertical or horizontal or an intermediate direction and of then enlarging a part of said bore or tunnel without withdrawing the apparatus from the ground.

In the forms of apparatus previously used in the art, it has been found necessary in 20 many kinds of operations to enlarge the drill hole of a tunnel or well usually at the forward end of the hole, so as to provide a larger capacity for the accumulation of water or oil in a well or for the placing of 25 machinery or of explosives at the end of a tunnel or shaft. In performing this operation it has been the custom to drill the hole, withdraw the drilling apparatus, then insert an expanding reamer and enlarge the 30 bore in a separate operation. This method has been found to be a very expensive one, in that a larger amount of time is usually required for the two separate operations and a great deal of expense is also involved. 35 The element of time is of a special consequence in drilling bores in undermining the enemy's trenches in warfare where a delay of a few hours may be of vital importance. It is to overcome this objection and to combine a drilling and a cavating or enlarging 40 operation so that the two acts may be performed in one continuous operation that the present device was invented. The principal object of the present improvement is hence 45 to provide a device for enlarging or cavating the end of a drill hole or bore without withdrawing the main or pilot drill from the ground.

Another object is to provide a reaming 50 or enlarging mechanism which may be maintained inoperatively within the hollow drill stem during the drilling of the bore, and which is adapted to be easily forced forward into operative position when it is desired to enlarge the end of the bore.

Another object is to provide a pilot drill

which is easily disconnected from the drill stem, and an enlarging or expanding reamer within the drill stem which can be advanced by fluid pressure into operating position to 60 cavate the end of the bore.

Another object is to provide a new and improved method of enlarging or cavating a bore or tunnel without withdrawing the drill from the ground and with the consequent valuable decrease in the amount of 65 time and expense necessary for the complete operation.

Other objects to be accomplished by my improved apparatus will more clearly appear in the description which follows.

My said invention is fully shown, described and claimed in the following specification and claims, of which the accompanying drawings form a part, wherein similar 75 reference letters or numerals of reference designate like or equivalent parts, wherever found throughout the several views, and in which:—

Figure 1 is a view in central longitudinal 80 section of my improved cavating mechanism, showing one of the enlarging-blades extended into operative position; such view being taken substantially on the line 1—1 of Fig. 2, looking from left to right thereof; 85

Fig. 2 is a like side view of the same mechanism, in substantially central longitudinal section, taken at a right angle to the section shown in Fig. 1, also looking from left to right.

Fig. 3 is a side perspective view in detail of the mechanism supporting sleeve removed, looking from left to right of Fig. 1;

Fig. 4 is a longitudinal vertical view thereof, taken on the same section as Fig. 1, with 95 the pilot-boring-bit removed, showing the expanding cavating-bit mechanism in its normal non-working position, and ready to be lowered into the expanding and cutting position;

Fig. 5 is a view in perspective, showing the upper strengthening sleeve in position, the bottom portion of which sleeve appears in section at the top of Fig. 4;

Fig. 6 is a view of the parts shown in 105 Fig. 5, taken in longitudinal vertical section.

Fig. 7 is a bottom plan view showing the expanding bit-mechanism in the fully expanded position.

Fig. 8 is a sectional top view of such mechanism, taken substantially on the line

8—8 of Fig. 1; Fig. 9 is a like section thereof taken substantially on the line 9—9 of Fig. 2, looking upward, the expanding caving blades being removed.

5 Fig. 10 is a side detail view, and Fig. 11 a like side face view of the upper securing the head end of one of the expanding boring blades;

10 Fig. 12 is a detail side view in central longitudinal section, of the cutting end of one of the blades of the simple one piece form shown in Figs. 1, 2, 7 and 8;

15 Fig. 13 is a view in central longitudinal section of the bottom portion of an artesian-well vertical bore-hole showing my improved enlarging cavating-bit mechanism in the cavating position therein; the pilot-boring-bit being shown disengaged therefrom and at the bottom of the pilot-bore;

20 Fig. 14 is a side perspective face view; and Fig. 15 a like view of the mechanism shown in Fig. 14, looking toward the right of Fig. 14 in the direction of the arrow, of a modified form of my improved expanding cavating-bit; and Fig. 16 is a bottom view of such modified form of my improved expanding cavating-bit. A modified form of the screw-joint between the main or pilot-boring-bit and its sleeve is shown in Fig. 25 30 35 40 45 50 55

17, while Fig. 18 is a top-plan view of the screw-shank portion of the pilot-boring-bit removed from the sleeve B.

Referring to the drawings, in the preferred embodiment of my improved cavating apparatus, the end of the drill stem is provided with any common form of bit or drill head, represented in Fig. 13 by the character A. This bit is adapted to be attached to the forward end of a hollow drill stem by any easily detachable means. In the present form I have shown a threaded or screw attachment for this purpose. The threaded upper portion of the bit is adapted to be screwed into an interior thread on the drill stem, and may be either cylindrical, as shown in Fig. 13, or somewhat tapering, as shown in Fig. 17, the advantage of the tapering form being that a few reverse turns of the drill rod only are necessary to release the bit from the drill stem. In either case the upper part of the bit is provided with a shoulder, 14, which is adapted, when the bit is tightened in place, to contact with the shoulder, 15, on the sleeve, or housing, B, on the drill stem. As an additional means for preventing the bit from becoming screwed in too tightly, a projection or lug, 14', which tightens into contact with the co-operating lug, 15', on the sleeve, B, is used. Provision is thus made for a joint between the bit and the drill stem which may be easily released by turning the drill stem in a direction opposite to that used in the operation of the bit. While this is my preferred form of easily releasable connec-

tion, other means may readily be adopted, as may be clearly seen. The pilot bit, when released, is allowed to remain in the end of the hole.

The cavating or enlarging mechanism is contained in a special housing in the drill stem above the bit. This housing is composed of a main section, 6, made up of two parts, the lower part, B, being attached to the upper part by a threaded connection, as shown at 4 in Fig. 4, the lower part, B, being internally threaded to fit over the lower threaded end, 5, of the upper section 6. This section or tube, is in turn, threaded to the exterior of the main drill stem D. In the lower part of the housing, B, two opposite slots, 2, are provided, through which the blades, 7, of the cavating mechanism may project. These slots are not diametrically opposite, but are off-set or staggered, as shown in Figs. 2, 7 and 8. The upper wall of the slot, 2, is inclined or beveled, as shown at 3, Fig. 1, to furnish a bearing for the blade, 7, when said blade is fully extended. Within the housing, B, is the cavating mechanism mounted in a barrel or tube, F. During the drilling operation this tube is withdrawn somewhat within the main drill stem in the manner shown in Fig. 4. When the drilling operation has been completed and the bit detached, the cavating tool is advanced into operative position, as shown particularly in Figs. 1 and 2.

At the upper end of the tube, F, is provided a driving piston head, 11, fitting detachably to the tube, F, by means of a downwardly threaded nipple 11'. In the center of the disk of the piston, 11, is an upwardly extended collar, 13, around which are mounted the packing piston rings, 12, separated by washer, 14. Above the upper piston ring, 12, is a washer, 15", held in place by a nut, 16, threaded on to the upper end of the upwardly extending collar. The collar, 13, furnishes a bearing for the lift rod, 26, which extends downwardly through the collar and the piston head, 11, to the lower piston head, 18, and is provided at its lower end with an enlargement or head, 27. At the upper end of the said rod, 26, is threaded a cable ring, 27', to which is adapted to be attached the cable, 28, which, while the cavating mechanism is inoperative, serves to support the same in its upper position against the action of the downward current of flushing water. Between these two piston heads, 18 and 11, and adapted to space the same resiliently apart, is the spiral spring 30, said spring, 30, being seated at its upper end in a grooved washer, 29, and at its lower end in a like washer, 29'. The pressure of the helical spring, 30, tends to normally force the lower piston head toward the lower end of the carrier 130

sleeve, F, and the blade, 7, outwardly into cavating position.

To provide a channel for the current of water usually used in this form of drill head to wash away the muck or detritus, a hole is formed through the registering washers and piston rings, 12, 15"; as shown at 17, and a like channel is formed in the lower piston head.

10 The reaming blades are mounted within the tube, F, as follows:

Opposite lugs, 19, project downwardly from the lower piston head, 18, furnishing a support for a pivoting spindle or shaft, 20, 15 mounted transversely of the tube in said lugs 19. Said shaft, 20, provides a bearing for intermediate links 21, pivoted at one end to the said shaft 20, and at the other end to the spindle, or shaft, 22, to which is pivotally attached the upper end of the blade, 7. The blades, 7, are pivotally mounted in the tube, F, by means of a shaft, 24, below and in vertical alinement with the aforesaid shaft, 20. The blades, 7, are elongated, flat 25 bars of steel, provided at their lower ends, 8, with curved or beveled cutting teeth, 7', in one embodiment, although the cutting teeth may have other forms, as shown in Figs. 13 and 14. The upper end, 23, of 30 each of the blades is cut away on the inner side, as at 32, in Figs. 10 and 11, to provide operating space for the links 21. The upper end of the blade is somewhat recurved and beveled, as shown at 33, for purposes 35 which will now be explained:

When the lower part of the blade is extended through the slot, 2, the upper part of the blade passes outwardly through the inner tube, F, through a slot or passage- 40 way, 31, provided therein, and contacts with the outer housing, B. In the said housing, B, to receive the head of the said blade, is arranged a recess, 36, the top of which is beveled to provide a bearing surface, and 45 the lower part of which is recurved so as to provide an upwardly inclined groove for a similarly recurved portion of the head, 23. To facilitate the withdrawal of the cavating mechanism from the bore after the 50 completion of the cavating operation, the carrier sleeve, F, has the partition, 30", Figs. 1 and 3, forming a division between the head receiving slots, 31, and the slots, 25, of the V-shaped form in cross- 55 section, shown in Figs. 1 and 2. The upper face of each slot 25 is on the same angle to the axis of the sleeve, as is the upper wall, 3, of each blade slot, 2, of the drill holder sleeve. The blade heads are of the shape 60 shown in Figs. 10 and 11, having the link recesses 32. The slide face 33 is of such an angle that when the blades are thrown out of the slots, 2, such bearing face is in abutment with the wall of the pilot bit sleeve, B, 65 the heads passing through the slots, 31, of

the carrier sleeve, F, and into the annular space at the bottom edge of the main sleeve 6.

The modified form of construction of my improved expanding bore enlarging and cavating bit shown in Figs. 14, 15 and 16, 70 differs from the simpler form shown in the other figures in that the blades 7 are provided with revoluble toothed cutter-wheels 47, usually of the bevel-gear wheel or cone-frustum form shown; which are revolubly supported on short shafts or pins 46. Such wheels are so mounted that the bases will form the cutting edges thereof when rotated to the right with the hands of a watch; and only the wheels have to be renewed, and 75 can be easily kept sharp by grinding. Such wheels are made of very hard and high tempered steels, such as chrome or vanadium ferric alloys, and they work well in the hardest of rock formation such as apatite, etc. 80

In the operation of this device the well or bore is drilled either downwardly or horizontally in the ground by means of the pilot bit A. To provide against the caving in of the sides of the drill hole an outer tube, C, 90 is used. Such tube has at its lower end a drive shoe, G, sharpened somewhat at its lower edge so that it may be driven forward periodically with the progress of the bit. During this drilling operation a stream 95 of water is pumped forcibly downward inside of the drill tube. The said stream is dashed against the bottom of the drill hole and circulated back upwardly outside of the drill stem, carrying with it the crushed 100 material cut away by the drill. In order to provide a proper channel for this upwardly ascending stream, and also at the same time to strengthen the connection between the lower housing, B, and the drill stem, D, 105 and to furnish a centering device for the same, I have provided a strengthening sleeve, E, the exterior surface of which is spirally grooved, as shown at 39 in Fig. 13. Said sleeve, E, is ratcheted at the top and 110 bottom, as shown at 10, 10', the ratchet teeth facing in the direction of the rotation of the drill rod. In this case it is a clock-wise rotation. The ratchet teeth and grooves cause a stirring up and constant agitation 115 of the muck-laden water and a swirl in the bore above and below such sleeve E.

When the drilling operation has been completed the drill stem is held firmly downward and rotated in the opposite direction 120 for several turns. The bit is thereby unscrewed and released from the drill stem, after which the drill stem is withdrawn slightly and the reamer blades forced into operative position. This is done by means 125 of fluid pressure exerted downwardly against the piston head, 11, or simply by the force of gravity thereon. The cable, 28, is released for the proper distance, allowing the tube, F, and the cavating apparatus con- 130

5 nected therewith to be advanced a proper distance so as to release the blades. In the inoperative position of the cavating mechanism, the downward thrust of the spring, 30,
10 5 holds the blades firmly against the sides of the housing, B. When this mechanism is advanced into operative position the blades are rotated by means of the cable, 28, to adapt the blades to register with the slots, 2, at which point they are pressed outwardly by the spring until they contact with the beveled upper wall, 3, of the channel, 2. The head of the blade in this movement bears against the upper wall of the recess, 36,
15 10 and extends into the operative position therein shown in Fig. 1. The drill stem is then rotated as before and the blades, 7, gradually cut away the earth from the inner periphery of the hole. It is to be understood, of course, that the cavating blades do not at once reach their fullest expansion due to their contact with the sides of the bore, but gradually work outwardly as they 20 15 ream away the sides of the hole.

25 20 While the cavation as shown in Fig. 13 is of short length, it is evident that the same may be made in the form of a long cylindrical enlargement of the pilot-bore, made either by withdrawing the casing upward or 30 25 backward the required distance, after dropping the pilot-bit; or by driving the pilot-bore down the required distance, releasing the pilot-bit at the bottom, and withdrawing the cavating bit up to the casing-shoe; 35 30 expanding the cavating bit-mechanism, and boring down; this being especially true when the jar or churn form of drill is used; but it is also evident that in this form of 40 35 rotating bits work may in some formations be done by starting the enlargement or cavation bore at the end or bottom and drawing the drill upward or backward.

I claim:—

1. In a drilling apparatus of the class described, a pilot bit; supporting mechanism for actuating the pilot bit; mechanism carried down with the pilot bit for enlarging and expanding the pilot bore, without removal of the drilling apparatus, when the 45 50 proper point is reached; and a support passing out through the supporting mechanism normally retaining the expanding mechanism in a non-operative position within the pilot bit mechanism support; and means whereby such enlarging mechanism may be forced forward into operative position when the desired point or stratum is reached.

2. In a drilling apparatus of the class described, a pilot bit; supporting mechanism 60 65 for actuating the pilot bit; mechanism carried down with the pilot bit for expanding the pilot bore, without removal of the drilling apparatus, when the proper point is reached; and a supporting cable passing out through the supporting mechanism normally

70 retaining the expanding mechanism in a non-operative position within the pilot bit mechanism support, and means whereby such expanding mechanism may be forced forward into operative position when the 70 desired point or stratum is reached.

3. In a drilling apparatus, a pilot bit, a supporting mechanism for actuating said pilot bit, adapted to be rotated in one direction to cut the pilot or main bore, and in 75 the reverse direction in order to release and abandon the pilot bit in the bottom or end of the main pilot bore, mechanism carried in with the pilot bit supporting mechanism for enlarging and expanding the pilot bore 80 without removal of the drilling apparatus, when the proper point is reached; means for bringing the expanding mechanism into operative position upon release of the main pilot bit, whereupon the supporting mechanism may be again rotated for causing enlargement of the main bore above the abandoned bit; and means for withdrawing the enlarging mechanism.

4. In a drilling apparatus, a bit sleeve, a 90 pilot bit secured to the bit sleeve in such manner that by rotating such bit sleeve in the reverse direction to the drilling rotation the pilot bit will be released from such bit sleeve and abandoned in the bottom of the 95 bore, and an excavating means for enlarging the pilot bore above the abandoned pilot bit, adapted to be advanced upon the release and abandonment of the pilot bit into the operative position previously occupied 100 by said bit.

5. In a drilling apparatus, a drill, a well casing, a combined centering and strengthening sleeve spaced behind the drill for centering the drilling mechanism within the 105 hole, said sleeve comprising a longitudinal tube adapted to bear throughout its length on the inner surface of the well casing, and having grooves in its outer surface for the purpose described.

6. In a device of the character described a drill stem, a drill thereon, a longitudinal centering and strengthening sleeve around said drill stem and spaced behind the drill, said sleeve serving to direct the action of the 115 drill, and external grooves in said sleeve to furnish an exit for the flushing water.

7. In a drilling apparatus of the class described, a combined centering and strengthening sleeve centering the drill mechanism 120 within the bore; a hollow drill rod for supplying fluid under pressure to the point of drilling, which fluid carries the drill muck up by the peripheral wall of the drilling mechanism and by that of the drill rod; the 125 combined centering and strengthening sleeve being provided on its outer periphery with fluid outlet grooves extending longitudinally thereon, rifled or spiraled, to assist in the outflow of the muck laden fluid stream, such 130

strengthening and centering sleeve being ratcheted at the top and bottom to assist in the agitation and removal of the outward flow of the muck laden fluid.

5 8. A bore enlarging mechanism comprising a support in the form of a sleeve, or connected sleeves; a cutting blade or blades adapted to enlarge the pilot bore; and means for yieldingly forcing such cutting blade or 70
10 blades outward through the forward end of the support into the enlarging position when the desired point is reached.

9. A bore enlarging mechanism comprising a support in the form of a sleeve or connected sleeves; a cutting blade or blades 75
15 adapted to enlarge a main bore; and means for yieldingly forcing such cutting blade or blades forward through the open end of the sleeve into the enlarging position, and for 20
20 retracting the cutting blades into small space to permit of the enlarging mechanism being drawn up out of the bore.

10. In an expanding reamer, a cable supported sleeve, reaming blades pivoted resiliently therein, said blades normally held inactive within the line of the sleeve and adapted to be projected into active position by fluid pressure on the sleeve.

11. In a drilling apparatus of the class 30
35 described, a pilot drill supporting drill sleeve having end slots and adapted to be removably secured to the pilot drill; a main sleeve screwed upon said drill sleeve, an expanding drilling mechanism, cutting blades 40
45 pivotally mounted therein and adapted to be forced out through the end of the drill sleeve into enlarging position; and means for automatically forcing such blades yieldingly outward through such end slots upon being brought into registry therewith.

12. In a drilling apparatus of the class described, a pilot drill supporting drill sleeve having end slots and adapted to be removably secured to the pilot drill; a main 50
55 sleeve screwed upon said drill sleeve; an expanding drilling mechanism, cutting blades adapted to be forced out through the end slots into expanding position by fluid pressure, and means for automatically forcing such blades yieldingly outward through such end slots upon being brought into registry therewith.

13. In a drilling apparatus of the class described, an expanding reamer comprising 55
60 a reciprocating sleeve having at the lower end blade receiving slots, a cavating mechanism, comprising a piston reciprocating in the reciprocating sleeve; and a bore expanding blade or blades supported by the reciprocating piston in such manner that when the reciprocating sleeve is drawn upward the expanding blade or blades will be automatically withdrawn into such reciprocating sleeve.

65 14. In a drilling apparatus of the class

described, a hollow cylindrical rod; a drill supporting sleeve secured to the lower end of the rod; a pilot cutting bit secured to the lower end of the drill sleeve in such manner that the same may be disconnected therefrom without withdrawing the drilling apparatus, when the desired length of bore has been attained; and a bore enlarging expanding drill, adapted to be lowered and expanded into drilling position upon the release of the pilot bit, normally supported within the drill supporting sleeve during the pilot boring.

15. In a drilling apparatus of the class described, a reciprocating sleeve; a piston 80
85 adapted to reciprocate in the reciprocating sleeve; means normally pressing such piston to the outer open end of the sleeve; and a cutting blade or blades pivotally supported by the sleeve pivotally connected to the reciprocating piston by a link connection, so as to be thrown out of the reciprocating sleeve and into the expanded and cutting position when in proper position for expanding the pilot bore, upon the forcing down or 90
95 outward of the reciprocating piston.

16. In a drilling apparatus of the class described, a supporting drill sleeve adapted to carry at the lower end a pilot boring bit or drill; a sleeve reciprocating in the supporting drill sleeve; a secondary bore expanding and cavating mechanism mounted in the reciprocating sleeve; means whereby the reciprocating sleeve may be forced to the bottom of the supporting drill sleeve; and means for forcing the cavating mechanism laterally from the bottom of the reciprocating sleeve, whereby the same is brought into the expanding position, so as to enlarge the pilot bore.

100
105 17. In a drilling apparatus of the class described, a supporting drill sleeve adapted to carry at the lower end a pilot-boring bit or drill; a sleeve reciprocating in the supporting drill sleeve; a secondary bore expanding mechanism mounted in the reciprocating sleeve; means whereby the reciprocating sleeve may be forced to the bottom of the supporting drill sleeve; and hydraulic means for forcing the expanding mechanism from the bottom or breast end of the reciprocating sleeve, and expanding the same on such movement of the reciprocating sleeve.

110
115 18. In a drilling apparatus of the class described, a supporting drill sleeve slotted at the end adapted to carry at the lower end a pilot drill; a like slotted sleeve reciprocating in the supporting drill sleeve; a secondary bore expanding mechanism mounted in the reciprocating sleeve having an expanding boring blade, or blades; means whereby the reciprocating sleeve may be forced to the bottom of the supporting drill sleeve; and means for forcing the expanding blade or blades into the expanding position so as 120
125 130

to enlarge the pilot bore when the supporting drill sleeve is rotated.

19. In a drilling apparatus of the class described, a supporting drill sleeve slotted at the end, adapted to carry at the lower end a pilot drill; a like slotted sleeve reciprocating in the supporting drill sleeve; a secondary bore expanding mechanism mounted in the reciprocating sleeve having an expanding boring blade, or blades, means whereby the reciprocating sleeve may be forced to the bottom of the supporting drill sleeve; means for rotating the reciprocating sleeve within the supporting drill sleeve so as to bring the blade slot or slots thereof into registry with the slot or slots of the drill sleeve; and means for then automatically throwing the blade or blades outward through the slot or slots of the supporting drill sleeve.
20. In a drilling apparatus of the class described, a supporting drill sleeve; a sleeve reciprocating in the supporting drill sleeve; a piston reciprocating in the reciprocating sleeve, a rod passing through the piston and through the head of the reciprocating sleeve; means for supporting the rod in a raised position in the supporting drill sleeve and for lowering the same; a coil-spring surrounding the supporting rod interposed between the reciprocating piston and the head of the reciprocating sleeve, so as to normally force the piston toward the bottom open end of the supporting drill sleeve, and a movable main bore expanding bit or bits, supported below the piston in the reciprocating sleeve, thrown into the bore expanding position upon the downward movement of the reciprocating sleeve by the action of the spring upon the piston.
21. In a drilling apparatus of the class described, a supporting drill sleeve; a sleeve reciprocating in the supporting drill sleeve; a piston reciprocating in the reciprocating sleeve, a rod passing through the piston and through the head of the reciprocating sleeve; means for supporting the rod in a raised position in the supporting drill sleeve and for lowering the same; a coil-spring surrounding the rod interposed between the piston and the head of the reciprocating sleeve, so as to normally force the piston toward the bottom open end of the reciprocating sleeve; and a movable cavating bit or bits supported below the piston in the reciprocating sleeve, thrown into the cavating position upon the downward movement of the reciprocating sleeve by the action of the spring upon the piston, the head of the reciprocating sleeve and the piston each having a perforation or perforations to permit of fluid passing down through the sleeve; and a hydraulic packing, forming a fluid tight connection between the head of the reciprocating sleeve, and the inner surface of the supporting drill sleeve, whereby upon

the release of the supporting means of the rod, fluid under pressure while passing freely through the sleeve will force the entire cavating mechanism down and out of the supporting drill sleeve into the cavating position.

22. In a drilling apparatus of the class described, a supporting drill sleeve; a sleeve reciprocating in the supporting drill sleeve; a piston reciprocating in the reciprocating sleeve; a rod passing through the piston and through the head of the reciprocating sleeve; means for supporting the rod and reciprocating sleeve in a raised position in the supporting drill sleeve and for lowering the same therein; a coil spring surrounding the rod interposed between the piston and the head of the reciprocating sleeve, so as to normally force the piston toward the bottom open end of the reciprocating sleeve; and a movable cavating bit, or bits supported below the piston in the reciprocating sleeve thrown into the cavating position upon the downward movement of the reciprocating sleeve by the action of the spring upon the piston, such piston and the head of the reciprocating sleeve having each a perforation or perforations to permit of fluid passing down through the sleeve; and a hydraulic packing forming a fluid tight connection between the reciprocating sleeve and the inner surface of the supporting drill sleeve, whereby upon the release of the supporting means of the rod fluid under pressure while passing freely through the reciprocating sleeve, will force the entire cavating mechanism down and out of the supporting sleeve into the cavating position; blade slots in the reciprocating sleeve to receive the heads of the cavating blades, normally holding the heads of the blades therein; and like slots in the supporting drill sleeve ending at the upper end in inclined slide faces to permit of the blade or blades being retracted into the reciprocating sleeve upon the device being drawn upward in the supporting drill sleeve into which slots the heads of the blades are forced by the action of the coil spring when the heads are brought into registry therewith.

23. In a drilling apparatus of the class described, a sleeve; a head closing one end of the sleeve; a fluid passage through the head leading to the interior of the sleeve; a piston reciprocating in the sleeve; a coil spring interposed between the piston and the head, a supporting rod normally holding the spring in compression through the piston; a cutting blade or blades pivoted to the sleeve and connected by a pivoted link with the piston; and means for raising and lowering the piston and for rotating the same.

24. In a bore enlarging device, a drill stem, a sleeve thereon, slotted at the forward end, expanding reaming blades supported

100

105

110

115

120

125

130

within the sleeve and adapted to be forced out by a fluid under pressure to the forward end thereof, and a spring for projecting the blades from said slots into active position.

25. In a device of the kind described, a rotatable hollow drill stem, a sleeve reciprocatable therein, said sleeve having a slot in the forward end, a supporting member in 10 said sleeve normally held resiliently toward said forward end, two bore expanding blades pivoted to said supporting member and forced into expanded position through said slots by the forward movement of said supporting member.

26. In a bore enlarging device, comprising a housing, an expanding blade or blades mounted on a plunger adapted to be forced forward to project said blades through the 20 forward end of said housing and a toothed conico-frustum cutting wheel for each revolvably mounted on the forward end thereof.

27. In a drilling apparatus of the class described, a drill stem, a reciprocating sleeve 25 in said drill stem provided with an end slot; a movable member normally pressed toward the open end of the sleeve, means acting to so press the member, and a plurality of movable bore expanding blades secured in the 30 reciprocating sleeve, and forced into the expanding position by the forward movement of the movable member.

28. In a drilling apparatus of the class described, a reciprocating sleeve; an expanding 35 reamer supported resiliently thereby, a head closing one end of the sleeve; a passage through the head leading through the interior of the sleeve to direct the flow of fluid upon the reamer, and a peripheral packing carried by the head.

29. In a drilling apparatus of the class described, a reciprocating sleeve; an expanding 45 reamer connected thereto; a head closing one end of the sleeve; a passage through the head leading through the interior of the sleeve to direct the flow of fluid upon the reamer; and a hydraulic ring or rings carried by the head.

30. In a drilling apparatus of the class described, a reciprocating sleeve, a head closing 50 one end of the sleeve; a passage through the head leading to the interior of the sleeve; a piston in the reciprocating sleeve; a coil spring interposed between the piston and the head, a supporting rod normally holding the spring in compression through the piston; and a cutting blade or blades pivoted to the sleeve and connected by a pivoted link connection with the piston.

60 31. In a drilling apparatus of the class described, a pilot bit supporting sleeve, a bore expanding mechanism adapted to be thrust out into expanding position therefrom, reciprocatingly supported within the 65 supporting sleeve; and a pilot bit secured

to such supporting sleeve by a screw connection, in such manner that when the required depth has been reached, and the drill is in contact with the bottom of the bore by rotating the sleeve in reverse direction 70 to the boring rotation, such pilot bit will be released therefrom, whereupon the bore expanding mechanism may be brought into operative position.

32. In a drilling apparatus of the class 75 described, a pilot bit supporting sleeve; a bore enlarging mechanism adapted to be thrust out into boring position therefrom, reciprocatingly supported within the supporting sleeve; and a pilot bit secured to 80 such supporting sleeve by a screw connection, in such manner that when the required point has been reached, and the drill is in contact with the bottom of the bore, by rotating the sleeve in reverse direction to the 85 boring rotation, such pilot bit will be released therefrom, whereupon the bore expanding mechanism may be brought into operative position; a passage or passages being provided through the expanding mechanism to allow of free passage of fluid into 90 the bore, when either the pilot bit or the expanding mechanism are in operation.

33. In a drilling apparatus of the class 95 described, a pilot bit, supporting mechanism for actuating the pilot bit; mechanism carried down with the pilot bit for enlarging the pilot bore, without removal of the drilling apparatus, when the proper point is reached; and a support passing out through 100 the supporting mechanism normally supporting the enlarging mechanism in a non-operative position within the pilot bit supporting mechanism; and means whereby such mechanism may be forced into operative 105 position, when the desired point or stratum is reached, by fluid under pressure.

34. In a drilling apparatus of the class described, a pilot bit; supporting mechanism for actuating the pilot bit; mechanism carried down with the pilot bit for expanding 110 the pilot bore, without removal of the drilling apparatus, when the proper point is reached; and a supporting cable passing out through the supporting mechanism or drill rod normally supporting the expanding mechanism in a non-operative position within the pilot bit supporting mechanism, and means whereby such mechanism may be forced into operative position when the desired point or stratum is reached, such means being operated by a fluid under pressure.

35. In a drilling apparatus of the class 125 described, a pilot bit; supporting mechanism for actuating the pilot bit; mechanism carried down with the pilot bit for expanding the pilot-bore, without removal of the drilling apparatus, when the proper point is reached; and a supporting cable passing out 130 through the supporting mechanism or drill

- rod normally supporting the expanding mechanism in a non-operative position within the pilot bit supporting mechanism and means whereby the expanding mechanism 5 may be forced into operative position when the desired point or stratum is reached; the said mechanism adapted to be wholly withdrawn by said cable from the bore after the completion of the expanding operation.
- 10 36. In a drilling apparatus of the class described, a pilot bit; supporting mechanism or drill rod for actuating the pilot bit; mechanism carried down with the pilot bit for expanding the pilot bore, without removal of the drilling apparatus, when the proper point is reached; and a supporting cable passing out through the supporting mechanism normally supporting the expanding mechanism in a non-operative position
- 15 20 within the pilot bit supporting mechanism; and means whereby such mechanism may be forced into operative position when the desired point or stratum is reached, said cable removing the mechanism wholly from the bore after the completion of the enlarging 25 operation, by drawing the same out through the hollow supporting drill rod without the removal of such drill rod.
37. In a drilling apparatus of the class 30 described, a drill rod; a pilot drill supported by the drill rod; the bit being releasable from the drill rod; a cavating mechanism for enlarging the bore above the disconnected pilot bit without removal of the mechanism from the bore; means whereby the enlarging mechanism may be forced into working position upon the release of the pilot bit; and means for withdrawing the enlarging mechanism out of the bore without 40 removal of the drill rod.
38. The hereinbefore described method or process of drilling bores, comprising the following steps: (1) drilling a pilot bore to the required point by rotation of the pilot boring drill bit flushing the detritus from the hole by a stream of water under pressure; (2) releasing the pilot boring bit from the drill rod by reverse rotation, and withdrawing the drill rod free from the bit; and then 45 50 (3) forcing an expanding reamer into op-

erative position by fluid pressure and without removal of the boring mechanism from the bore, enlarging the bore above the disconnected pilot boring bit by rotation of the drill rod in the original direction of rotation.

39. The hereinbefore described method or process of drilling wells, comprising the following steps: (1) drilling a pilot bore to the fluid bearing strata by rotation of the pilot boring drill bit; (2) releasing the pilot boring bit from the drill rod; and raising the drill rod free from the bit; and then (3) forcing an expanding reamer into operative position by fluid pressure and without removal of the boring mechanism, enlarging the bore above the abandoned and disconnected pilot boring bit so as to increase the circumference and consequently the area of the percolating wall of the well, by rotation of the drill rod in the original pilot boring direction.

40. In a device of the class described, a pilot bore drill; a support for such drill; a bore enlarging mechanism normally carried in the support, the drill being secured to its support by a screw joint, provided with means for keeping such joint at all times a loose and easily movable one.

41. In a device of the class described, a hollow drill rod; a pilot bore drill supported by the drill rod, the joint between the two being a male and female screw tightened by rotation of the drilling rod in the drilling direction, adapted to be released by reverse rotation of the drilling motion when the pilot-boring drill is in contact with the breast being drilled; and a ratchet or ratchet-teeth, one upon the end of the support and the other upon the peripheral flange at the base of the screw thread of the pilot drill co-acting with one another in such manner as to keep the joint between such bit and its support a comparatively loose one.

HOWARD R. HUGHES.
